[57] CLAIM

The ornamental design for an arm protector, as shown and described.

DESCRIPTION

FIG. 1 is a Perspective View showing a first embodiment of my new design;

FIG. 2 is a top plan view thereof;

FIG. 3 is a right side elevation view, the left side being a mirror image thereof;

FIG. 4 is a bottom plan view thereof;

FIG. 5 is a front elevation view thereof;

FIG. 6 is a rear elevation view thereof;

FIG. 7 is a front and bottom perspective view thereof shown in condition of use on a human arm;

FIG. 8 is a front and bottom perspective view of a second embodiment of my new design;

FIG. 9 is a top plan view thereof;

FIG. 10 is a right side elevation view, the left side being a mirror image thereof;

FIG. 11 is a bottom plan view thereof;

FIG. 12 is a front elevation view thereof;

FIG. 13 is a rear elevation view thereof; and,

FIG. 14 is a front and bottom perspective view thereof shown in condition of use on a human arm.

The broken line showing of a human arm is for illustrative purposes only and forms no part of the claimed design.
